US00D965060S

(12) **United States Design Patent** (10) **Patent No.:** **US D965,060 S**
Ishio (45) **Date of Patent:** **** Sep. 27, 2022**

(54) **DOCUMENT FEEDER FOR COPIER**

(71) Applicant: **Toshiba Tec Kabushiki Kaisha**, Tokyo (JP)

(72) Inventor: **Hisaya Ishio**, Tokyo (JP)

(73) Assignee: **TOSHIBA TEC KABUSHIKI KAISHA**, Tokyo (JP)

(**) Term: **15 Years**

(21) Appl. No.: **29/707,867**

(22) Filed: **Oct. 1, 2019**

(30) **Foreign Application Priority Data**

Apr. 2, 2019 (JP) 2019-007216

(51) **LOC (13) Cl.** **18-99**

(57) **CLAIM**

I claim the ornamental design for a document feeder for copier, as shown and described.

DESCRIPTION

FIG. 1 is a front perspective view of a document feeder for copier showing the new design;

FIG. 2 is a front view of the document feeder for copier of FIG. 1;

FIG. 3 is a rear view of the document feeder for copier of FIG. 1;

FIG. 4 is a top view of the document feeder for copier of FIG. 1;

FIG. 5 is a bottom view of the document feeder for copier of FIG. 1;

FIG. 6 is a right side view of the document feeder for copier of FIG. 1; and,

FIG. 7 is a left side view of the document feeder for copier of FIG. 1.

The broken lines shown in the drawings depict portions of the document feeder for copier that form no part of the claimed design.
